ALL METAL AUTOMATIC COOLING TOWER

William J. Stolzer, Little Rock, Ark.

Application January 22, 1938, Serial No. 186,457

1 Claim. (Cl. 261—113)

This invention relates to an all metal automatic cooling tower for ice machines, bottling plants and other apparatus.

An object of the invention is to provide a novel cooling tower which will utilize the latent heat of evaporation to cool water ten to fifteen degrees cooler than air temperature with a resultant saving of power consumption on various types of machinery.

10 A further object is to provide apparatus including an all metal cooling tower and a regulating tank which will be formed of a few light strong and durable parts, which will be inexpensive to manufacture and install, and which will not easily get out of order.

With the above and other objects in view the invention consists of certain novel details of construction and combinations of parts hereinafter fully described and claimed, it being understood 20 that various modifications may be resorted to within the scope of the appended claim without departing from the spirit or sacrificing any of the advantages of the invention.

In the accompanying drawing forming part of 25 this specification,

Figure 1 is a vertical sectional view of a cooling tower, regulating tank, and connections, constructed in accordance with the invention.

Figure 2 is a plan view of the tower with the 30 spray cap removed.

Figure 3 is a cross sectional view taken on the line 3—3 of Figure 1 showing a spreader pipe on one of the bolts which connect the angle iron uprights.

35 Figure 4 is a cross sectional view taken on the line 4—4 of Figure 1 showing another of the connecting bolts without the spreader pipe thereon.

Referring now to the drawing in which like characters of reference designate similar parts 40 in the various views, 10 designates a regulating tank which may be disposed near the machine upon which the cooling system is to be installed. A water supply pipe 11 enters the tank and is equipped with an outlet pipe 12 which is supported upon the bottom of the tank. A valve 13 45 controls water supplied to the tank and a float 14 controls the valve to maintain a predetermined water level in the tank.

A baffle 15 extends downward in the tank to 50 near the bottom of the tank. The water to be cooled is drawn from the tank by a conventional pump 16 which is preferably driven by an electric motor 17. The outlet pipe 18 of the pump is conducted preferably through the roof 19 of 55 the building where the device is to be used and

rises to the top of the cooling tower about to be described, as best shown in Figure 1.

The cooling tower comprises four upright angle irons 20 which form the corner supports of the tower and which are connected together by bolts 5 21 extending horizontally in superposed planes at a sufficient distance apart to form hangers for a stack of pans 22. Certain of the bolts have pipes 23 sleeved upon them to form spreaders or spacers for the corner angle irons 20. As 10 best shown by dotted lines in Figure 1, three of such pipespreaders are illustrated.

The cooling pans are provided with rolled rims 24 through which the bolts 21 are passed to suspend the pans one above the other. Each cooling 15 pan is provided with a reticulate bottom 25. The bottom 26 of the lowermost pan is imperforate since this pan forms a collection pan. An outlet pipe 27 leads from the bottom 26 of the lowermost pan to the top of the regulating tank 20 10.

The water pipe 18 from the pump is provided with a transversely disposed extension 28 at the upper end which extends to about the center of the top of the tower and is terminally equipped 25 with a stand pipe 29 which rises axially in a pyramidal shaped spray cap 30. For securing the stand pipe and spray cap in place preferably four threaded rods 31 are disposed diagonally across the tower and are secured to the corner 30 supports 20 by nuts 32. The rods are connected together at the center of the top of the tower by an annular collar 33 which is sleeved on the stand pipe 29 and supports the stand pipe in place.

35 The spray cap 30 is provided at the bottom with depending tabs 34 to which clips 35 are bolted, these clips having rounded extremities which embrace the rods 31.

A branch pipe 36 leads from the water pipe 18 40 at a point just above the collection pan 26 and is controlled by a valve 37 the stem 38 of which is passed through the roof 19 and disposed adjacent to the regulating tank 10.

In operation the water to be cooled is pumped 45 from the regulating tank 10 and forced upward through the pipe 18 and stand pipe 29 to impinge against the top of the spray cap 30. The mass of water in finely comminuted form is directed downwardly by the spray cap and escapes 50 progressively downward through the reticulate bottoms of the cooling pans in a mist or spray until the collecting pan is reached from which the cooled water is discharged back through the regulating tank through the pipe 27. While grav- 55

itating through the tower as just described the water is aerated and the latent heat of evaporation will cool the water ten to fifteen degrees cooler than air temperature. In practice it has been found that the water lost by evaporation is about ten percent.

The valve 37 is open when the tower is being used in freezing weather. In such weather the water need not rise above the pipe 36 for only a short time period for aeration and cooling will then be necessary.

From the above description it is thought that the construction and operation of the invention will be fully understood without further explanation.

15 What is claimed is:

A cooling tower including metal uprights, bolts connecting the uprights at intervals, said bolts being disposed to form superposed rectangular

hangers for pans, spreader pipes on certain of the bolts butted at the ends against the uprights, pans having rolled rims engaged over said bolts to suspend the pans in a stack spaced apart from each other, said pans having reticulate bottoms 5 to permit the contents to escape and be aerated, a collection pan carried by the lowermost hanger beneath the reticulate bottomed pans, an outlet pipe for the collection pan, an inlet pipe directed at the top to discharge its contents upwardly 10 above the uppermost pan and in the axis of the tower, a spray cap connected to the tower at the top thereof for deflecting water downward from the outlet pipe to the pans, and a valve controlled branch pipe connected to the inlet pipes 15 at the top of the lowermost pan adapted to direct the liquid to be cooled in freezing weather into the lowermost pan.

WILLIAM J. STOLZER.
